UNITED STATES PATENT OFFICE.

ARTHUR R. MOSLER, OF NEW YORK, N. Y., ASSIGNOR TO A. R. MOSLER & CO., OF NEW YORK, N. Y., A CORPORATION OF NEW YORK.

GASKET.

1,210,193.

Specification of Letters Patent. Patented Dec. 26, 1916.

Original application filed November 19, 1908, Serial No. 463,475. Divided and this application filed February 23, 1912. Serial No. 679,384.

To all whom it may concern:

Be it known that I, ARTHUR R. MOSLER, a citizen of the United States, and resident of the borough of Manhattan, in the city and State of New York, have invented a new and useful Improvement in Gaskets, of which the following is a specification.

This invention relates to packing rings or gaskets, and more particularly to packing rings or gaskets for use in so-called spark plugs or igniters for explosive hydrocarbon engines.

The objects of this invention are to provide articles of this character which will be perfectly and permanently gas-tight, and will stand the effects to which they are subjected when used for the purpose specifically referred to, without deterioration.

Broadly considered, this invention contemplates a packing ring or gasket composed of cord consisting wholly or in part of asbestos, which cord is coiled into appropriate form and then wound transversely about the previously formed coils.

This application is a division of my application Serial No. 463,475, filed November 19, 1908, for spark plugs.

A practical embodiment of the invention is represented in the accompanying drawings, in which,

Figure 1 represents a longitudinal section of a spark plug with the gaskets shown in position, Fig. 2 represents a detail view, partly in section, showing the cord which has a wire core, Fig. 3 represents a similar view showing the cord composed entirely of asbestos, Fig. 4 represents a washer or gasket partially completed, composed of the cord having a wire core, Fig. 5 represents the same gasket completed, Fig. 6 represents a view similar to Fig. 4, showing the cord composed entirely of asbestos, and Fig. 7 represents a view similar to Fig. 5, showing the pure asbestos cord.

In order to render spark plugs for explosive hydrocarbon engines gas-tight, it has been found necessary to provide gaskets at various points. Certain of these gaskets must be affected by different influences from the others because of their more proximate location to the area of combustion, and hence their subjection to the great heat incidental thereto. On the other hand, some of the gaskets are located at points

where the spark plug is commonly separated for inspection or cleaning, and these gaskets are consequently liable to be worn or injured by the assembly and disassembly of the parts between which they are located. I have found that asbestos forms the best packing ring for application at points closest to the combustion chamber; and that asbestos having a strong center or core, such as copper wire, is best adapted for those places where it is subjected to the wear incidental to separation of the plug.

Referring to the drawings, the shell of the plug is denoted by 1, the insulating block by 2, the conducting wire by 3. The insulating block 2 is provided with an enlarged central portion 4, and a screw cap 5 serves to hold the said block in proper position within the shell 1. As the construction of the spark plug itself forms no part of the present invention, it will not be further described.

In forming my improved gasket, which is to be composed of asbestos having a strong center or core, I preferably employ copper wire 6 having a relatively thick exterior coating or covering of asbestos 7. This cord is coiled into the appropriate form, which is generally circular, and into the proper size, which varies greatly according to different applications. The cord may be coiled a sufficient number of times to provide the required thickness for the washer, and then the cord is transversely wound, spirally and in an annular course, about the previously formed coils.

Fig. 4 shows the gasket after the coils have been made and when the transverse winding has just been begun. After the transverse winding is completed, the end of the cord may be inserted between some of the windings in order to finish off the gaskets, which will then be completed and will appear as represented in Fig. 5.

When making a gasket which is to be entirely composed of asbestos, I preferably select asbestos cord 8, as shown in enlarged view in Fig. 3, and this cord is coiled and wound into proper shape and size in exactly the same manner as previously described with regard to the cord having a copper wire core, Figs. 6 and 7, showing this gasket in course of construction and completion in a manner similar to that represented

in Figs. 4 and 5, with regard to the gasket containing the wire.

In use I preferably employ one of the pure asbestos gaskets 9 at the point in the spark plug which is most closely adjacent to the inner or igniting end of the latter, while I employ one of the gaskets 10 having the copper wire core, between the shell 1 and the cap 5 of the spark plug, as that is the point 10 where it will receive the greatest wear owing to the removal and replacing of the cap 5, when dismembering the spark plug.

I have found by experience that the gasket 10 which is composed of copper wire covered with asbestos, is extremely strong and elastic, so that it will withstand the compression incidental to the screwing down of the cap 5, and yet will expand slightly when the cap is removed, in order that it 20 may have again a slight yielding property when the cap 5 is replaced and hence may always provide a gas-tight joint. It has been found that most gaskets, when subject to such use, become too much compressed and rapidly wear out, thus losing their 25 effective quality.

The pure asbestos gasket 9, is enabled to withstand the great heat incident to the combustion in the cylinder of the engine 30 and by reason of the fact that it is coiled and wound as described, it will also preserve its qualities as a slightly yielding, elastic and very effective packing.

It will be understood that various changes 35 may be resorted to in the construction, form and arrangement of the packing ring without departing from the spirit and scope of

my invention; hence I do not wish to limit myself strictly to the form herein shown and described, but

What I claim is:

1. A packing ring composed of a cord of suitable material coiled in the direction of the axis of the ring, said coils being bound together by an outer wrapping of similar 45 material applied spirally and in an annular course.

2. A packing ring composed of an asbestos cord coiled in the direction of the axis of the ring, said coils being bound together by an outer wrapping of similar material applied spirally and in an annular 50 course.

3. A packing ring composed of a cord, having a copper wire center, coiled in the 55 direction of the axis of the ring, said coils being bound together by an outer wrapping of similar material applied spirally and in an annular course.

4. A packing ring composed of an asbestos cord, having a copper wire center, coiled in the direction of the axis of the ring, said coils being bound together by an outer wrapping of similar material applied spirally and in an annular 60 course.

In testimony, that I claim the foregoing as my invention, I have signed my name in presence of two witnesses, this twentieth day of February, 1912.

ARTHUR R. MOSLER.
